UNITED STATES PATENT OFFICE

115,769

DESIGN FOR A PAIR OF SPECTACLES

Thomas J. Snavely, Peabody, Kans., assignor to
American Optical Company, Southbridge,
Mass., a voluntary association of Massachusetts

Application September 28, 1938, Serial No. 80,129

Term of patent 14 years

To all whom it may concern:

Be it known that I, Thomas J. Snavely, a citizen of the United States of America, residing at Peabody, in the county of Marion and State of Kansas, have invented a new, original, and ornamental Design for a Pair of Spectacles, of which the following is a specification, reference being made to the accompanying drawing, forming a part thereof.

Figure 1 is a front perspective view of a pair of spectacles; and

Figure 2 is a top plan view of the same, showing my new design, the temples being shown frag-

mentarily in Figure 1 for convenience of illustration.

The characteristic features of the design are shown in full lines in the drawing and constitute bar-like members adapted to blend into the temple supporting portions of the mounting so as to render the connection between said bar-like members and temple supporting portions substantially invisible when viewed from the front.

I claim:

The ornamental design for a pair of spectacles, substantially as shown and described.

THOMAS J. SNAVELY.
